Primary Examiner — Ricky Pham(74) *Attorney, Agent, or Firm* — Muncey, Geissler, Olds & Lowe, P.C.(57) **CLAIM**

The ornamental design for a cutting board, as shown and described.

DESCRIPTION

FIG. 1 is a perspective view of a cutting board according to the present invention.

FIG. 2 is a right side view of the cutting board of FIG. 1.

FIG. 3 is a left side view of the cutting board of FIG. 1.

FIG. 4 is a front side view of the cutting board of FIG. 1.

FIG. 5 is a rear side view of the cutting board of FIG. 1.

FIG. 6 is a top view of the cutting board of FIG. 1; and,

FIG. 7 is a bottom view of the cutting board of FIG. 1.

The dashed lines illustrate environment that does not form a part of the present invention, and no claim is made to the material illustrated with dashed lines.
